(57) **CLAIM**

We claim the ornamental design for a sand tire, as shown and described.

DESCRIPTION

FIG. 1 is a top, left-side perspective view of a sand tire showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged fragmentary view of the region labelled “8” shown in FIG. 1;

FIG. 9 is an enlarged fragmentary view of the region labelled “9” shown in FIG. 2; and,

FIG. 10 is an enlarged fragmentary view of the region labelled “10” shown in FIG. 5.

The even-length broken lines in the figures represent portions of the sand tire that form no part of the claimed design.
